(No Model.)

S. H. HOWLAND.

MACHINE FOR TURNING THE CHANNEL LIPS OF INSOLES.

No. 388,280.

Patented Aug. 21, 1888.

UNITED STATES PATENT OFFICE.

SAMUEL H. HOWLAND, OF NEW YORK, N. Y.

MACHINE FOR TURNING THE CHANNEL-LIPS OF INSOLES.

SPECIFICATION forming part of Letters Patent No. 388,280, dated August 21, 1883.

Application filed January 24, 1883. Serial No. 261,737. (No model.)

To all whom it may concern:

Be it known that I, SAMUEL H. HOWLAND, of the city and county of New York, in the State of New York, have invented a certain new and 5 Improved Lip-Turning Machine for Treating Insoles of Boots and Shoes, of which the following is a specification.

It is common to cut by hand or by machinery around the edge of an insole, so as to split the 10 edge of the leather or divide it into two nearly equal thicknesses, leaving one portion—that next to the foot—smooth and unaffected, and to turn up the other portion. This is usually done with the leather in a dampened and limbered condition, and no harm results if the 15 turning, instead of being arrested in an upright condition, is carried further, so as to fold the lip over upon the unsplit portion within it. My improved machine is intended to effect 20 this rapidly and perfectly.

I provide a beveled guide, which, as the insole, after being properly split around the edge, is presented to it, insinuates itself into the cut and lifts the lip. I provide a reciprocating 25 jaw, which next takes hold of the lip and turns it over and presses it down upon the unaffected portion of the insole. I provide two guides, one on each side of the reciprocating jaw. These hold the work better in position and 30 allow the operator to move the sole in either direction—that is, to the right or to the left. The jaw reciprocates actively, and by moving the insole by hand or machinery the entire lip is rapidly turned over and pressed down by 35 the successive compressions of the jaw. I provide adjustments which regulate the position of the guides and of the base, or support on which the insole rests, adapting it to greater or less thicknesses. I introduce a spring to 40 regulate the action and allow it to yield to temporary inequalities.

The invention applies more especially to the manufacture of what are known as "imitation hand-sewed shoes."

45 The accompanying drawings form a part of this specification, and represent what I consider the best means of carrying out the invention.

Figure 1 is a side elevation, and Fig. 2 is a plan view, of the entire machine. Fig. 3 is a 50 front view, and Fig. 4 is a vertical section on the line $x-x$ in Fig. 3.

Similar letters of reference indicate corre-

sponding parts in all the figures where they occur.

The bed-casting A is bolted down upon a 55 work-bench or other suitable support. (Not shown.)

B is a shaft rotated by a belt from any convenient power, running on a pulley, B'. An eccentric, B², fixed on shaft B takes hold by an 60 eccentric-strap, D', of a rod, D, equipped with nuts D² D³, a spring, E, and bearing-washers E', which engage with the upper arm, G', of a bell-crank lever, the lower arm, G², of which lever is the working-jaw, which performs the func- 65 tion of pressing down the lip.

M is the insole, M' the unaffected portion of the edge, and M² the lip which it is desired to turn over. The hub or center G of the lever G' G² is held by stout pivots A' A', tapped 70 through lugs in the bed and adjusted by jam-nuts A².

I is a casting held adjustably on the front face of the bed A, being steadied by vertical guides A³ at each side. Its upper end is di- 75 vided, forming two guides, I' I², which stand on opposite sides of the jaw G².

An adjustable slide, J, held on the front face of casting I and steadied on the latter by vertical guides J' at each side, carries a table, J², 80 which presents a flat upper surface at adjustable heights under the guides I' and I² and the vertical reciprocating jaw G². The slides I and J are both firmly held by a single bolt, K, inserted through the slots in the slides and 85 tapped into the bed A. The lower edges of the guides I' I² are beveled, as shown.

In the use of the machine the lip of the properly cut and dampened sole is first raised at one end by the finger or otherwise, and the 90 sole is laid upon the table J² and its edge M' thrust under the guides I' I², and the reciprocating jaw G² commences to press down on such portion of the lip M' as is presented thereto. Now, by moving the sole laterally to the right 95 or the left, keeping its edge M' under the guides I' I², successive portions of the lip as they are presented are lifted by the guides and turned over and pressed down by the jaw G². Thus the sole may be moved in either direction un- 100 til the entire lip M², commencing at one end, may be folded over and pressed down in the open position throughout its entire length.

The operation is rapid and efficient. It re-

quires but little skill. If a thicker lot of insoles are to be treated, the bolt K is slackened and the table J² is lowered and again secured. The piece I, with its guides I' I², may also be 5 raised and lowered to adjust their position relatively to the table J² or to the jaw G², or to both.

When any temporary increase of thickness is presented, the spring E yields and allows 10 the jaw G² to be arrested in a higher position, thus accommodating inequalities in the work.

The position in which the lever G' G² ordinarily acts may be varied by shifting the nuts D² D³ outward or inward on the rod D. The 15 tension of the spring E may be varied by setting the nut D³ backward or forward on the rod D. There may be a jam-nut behind each of the nuts D² and D³ to aid in maintaining them in position. I have shown a jam-nut, D⁴, 20 behind the nut D³.

The hole through the arm G', which receives the operating-rod D, is double-tapered, as shown, and the bearing-surfaces by which the nuts take hold on the arm G' are spheroidal, 25 and the inner faces of the bearing-washers E' are correspondingly spheroidal, thus accommodating the bearing to all positions of the lever.

C is a loose pulley, performing the usual 30 functions of such member.

Modifications may be made without departing from the principle or sacrificing the advantages of the invention.

Other means may be provided for holding and adjusting the position of the table J² and 35 of the guides I' I².

Parts of the invention may be used without the whole. I can dispense with the guide I² and operate only with the guide I', always moving the sole from the left to the right. I 40 prefer the whole, as shown.

I claim as my invention—

1. In a machine for turning the channel-lips of insoles, the beveled guide I' and table J², in combination with each other and with the jaw 45 G², reciprocated relatively to the table, adapted to turn over and press down the lip of an insole, substantially as and for the purposes herein specified.

2. In combination with the guide I', table 50 J², and reciprocating jaw G², the spring E, eccentric B², and rod D, arranged to operate the jaw with a yielding force, as herein specified.

3. The duplicate guides I' I², in combination with the reciprocating jaw G², table J², and 55 means, K, for adjusting the guides and table, arranged to serve substantially as herein specified.

In testimony whereof I have hereunto set my hand, at New York city, this 21st day of January, 1888, in the presence of two subscribing witnesses.

SAML. H. HOWLAND.
